EMULSIFYING APPARATUS

James Franklin Miller and Michael C. Jaskowski,
Pittsburgh, Pa., assignors to the United States
of America as represented by the Secretary of
the Army

Application May 23, 1950, Serial No. 163,644

4 Claims. (Cl. 259—57)

1

This invention relates to emulsifying apparatus, that is, apparatus for inverting one or a plurality of sealed containers of liquids under uniform conditions, so that the contents of the containers may be inspected, compared and perhaps measured to determine the per cent of emulsions formed from different mixtures of liquids in the several containers.

In an investigation of the emulsifying properties of various mixtures, remarkably inconsistent results were obtained because of the variables entering into the method of forming the emulsions. The time consumed, the energy expended, the type of agitation (whether stirring, shaking, or inversion), and the personal equation, all changed the final product. After much study, it was discovered that the most reproducible and regular results were obtained by the simplest technique of merely inverting a cylinder containing the concentrate and water and returning it to its original position. 100 ml. graduated glass cylinders were used and the emulsions were examined by placing the cylinders containing the emulsions in front of a light source. Stabilities of emulsions could be reproduced to about 5%, provided a single operator working with identical emulsion systems was active for short periods of time, say one hour. With different operators, widely different results were obtained even when they attempted to follow the same technique. Repeating the inversion produced results which were increasingly erratic as the number of inversions increased.

The invention provides a mechanically operated emulsifying rotator for a plurality of containers by means of which all the containers are subjected to the same agitation in the same time interval, so that the personal equation is eliminated, and an unskilled operator may get consistent results. Such a rotator may be used advantageously as an instrument for producing and observing emulsions in order to rate performance of emulsion concentrates, for specification testing purposes.

In the accompanying drawings forming a part of this specification—

Fig. 1 is a front elevation of a rotator embodying the invention;

Fig. 2 is a vertical section on line 2—2 of Fig. 1; and

Fig. 3 is a vertical section on line 3—3 of Fig. 1.

In the drawings, we have shown a rotator which in general consists of a support for a plurality of bottles or other transparent containers, power means for rotating the support through one or more revolutions as desired, and a source of light

2

arranged to transmit light through the bottles so that their contents may be inspected after such rotation. The bottle support includes a casing 5 open at the front side and closed at the bottom and the two ends, the casing top 6 having a lid 7 hinged as at 8 so that the casing may be opened at the top to give access to its interior for placement or removal of the bottles. Fixed within the casing at either end is a shaft bearing 9, 10, said bearings being aligned to support a shaft 11 and stub axle 12 aligned with shaft 11. An elongated bottle rack 13 is secured to shaft 11 at one end, and is fixed to the stub axle 12 at the other end; the arrangement being such that the longitudinal axis of the bottle rack 13 substantially coincides with the common axis of shaft 11 and stub axle 12. The bottle rack is open at the front and back to permit transmission of light therethrough, and has a light-reflecting surface such as milky "Plexiglas" 14 on which rest the lower ends of bottles or test-tubes 15. The "Plexiglas" sheet 14 extends beyond the confines of the bottle, as Fig. 3 clearly shows. A perforated bottle holder 16 is fixed 20 within the bottle rack and holds the bottles upright and equally spaced as shown. Stoppers 17 seal the upper ends of the bottles. To hold the stoppers tight, a sponge rubber mat 18 is fixed on the bottom of a strip 19 secured to a lid 20 hinged as at 21 to the top of the bottle rack. 25 Latches (not shown) may secure the lid 20 and thus hold the bottles immovably on the rack.

By the described construction one or more test tubes of bottles may be placed on the rack and held against relative movement, with no spillage 30 of its contents possible, while the rack is rotated one or more times on its longitudinal axis. A single rotation of the rack causes the bottle or bottles to be inverted and then restored to its original position. All the bottles are moved in the same manner and all are subjected to identical agitation or mixing; in fact, as the drawings indicate, each bottle is rotated about an axis which is half way between its upper and lower ends. After the rotation the bottles may be inspected with the aid of light from a source such as a pair of fluorescent tubes 24, 25 held on a support 26 including a reflector 27, with a light-diffusing panel 28 (such as milky "Plexiglas") placed in front of the tubes. The light transmitted through the "Plexiglas" panel 28 shines through the bottles or test tubes and reveals their contents. Some of the light strikes the reflecting surface 14 on which the bottles stand and is reflected into the interiors of the bottles, 50 to give an improved view of the contents. The

3

source of electric current and the usual light-controlling switch are not shown but will be understood without illustration.

To effect and control rotation of the bottle rack, several different mechanisms may be used. The one herein shown consists of an electric motor 30, a reduction gear box 31 coupled with the motor and driving a shaft 32 slowly, a coupling 33 directly connecting shaft 32 with shaft 11, a pinion 34 driven by shaft 32, a spur gear 35 driven by pinion 34, a "microswitch" or cut-off switch 36 connected into the motor circuit, and a pin 37 fixed to and extending out from gear 35 in any desired position (as by screw threads on its end, not shown, engaged in one of preferably ten tapped bores 38 in the gear) and adapted to depress the contact of the "microswitch" 36 once during each revolution of the gear to open the motor circuit. Now the pinion 34 may have sixteen teeth, while the spur gear may have 160 teeth, or a 1:10 ratio, making the spur gear rotate once for each ten rotations of the pinion. The bottle rack, of course, rotates synchronously with the pinion. Depending on the angular position of pin 37 relative to the "microswitch" at the start, the bottle rack will rotate from one to nine times before the parts are brought to rest. If a tenth rotation, or a larger number of rotations, are desired, the operator will swing the "microswitch" support 39 out of the way on its hinge 40 against the tensioned coil spring 41.

It will be appreciated by those skilled in the art that a group of light-sensitive cells may be arranged in front on the rotator, with the necessary circuits. By placing a light source of constant intensity at the rear so that the light will be directed through the emulsions to the cells, variations in the concentration of oil droplets will variably affect the light cells, and with the proper calibrated instruments the rate of "creaming" may be measured. Observation by the eye is capable of determining only large differences in droplet concentration, whereas light-sensitive cells would make possible the measurement of very small droplet concentration differences.

In actual use, the described apparatus has demonstrated its value for making emulsions of various mixtures and for visual inspection of the emulsions. The device is easily built, operated and kept in service. No particular skill is required and results are substantially uniform.

Obviously, a number of changes may be made in the described apparatus without departure from the spirit of the invention. Thus, in some instances natural light, for example, that from a window, may be used in lieu of the source of artificial light 24, 25 shown in the drawings. Other minor changes will occur to those skilled in the art.

What we claim is:

1. Emulsifying apparatus comprising a support which is open from one side to the other so that light may pass therethrough; a bottle holder inclosed by the support; means for clamping a bottle against movement on the bottle holder, means for rotatably mounting the bottle holder on the support so that the bottles are turned end over end when the bottle holder is rotated; power driven mechanism for rotating the bottle holder, said power driven mechanism including an electric motor, reduction gearing driven by said motor, and a shaft driven by said reduction gearing for rotating the bottle holder in one direction only; a switch electrically connected with said motor for opening the circuit of said motor;

60

70

75

4

means moved by said shaft to operate said switch to stop said motor, said last-named means being operator-adjustable to change the number of rotations permitted the bottle holder in each cycle of the machine; and a support upon which said circuit-opening switch is hingedly mounted in such position that the operator may swing the switch out of the path of said last-named means so that the bottle holder may then rotate as long as desired.

2. Emulsifying apparatus comprising a casing which is open from one side to the other so that light may pass therethrough; a bottle holder surrounded by the casing; means for clamping a bottle against movement on the bottle holder; means for rotatably mounting the bottle holder on the casing so that the bottle is turned end to end when the bottle holder is rotated; power driven mechanism for rotating the bottle holder; a light-diffusing plate mounted on the casing for cooperation with a bottle on the bottle holder, and light reflecting means provided on the bottle holder and disposed adjacent one end of the bottle and extending laterally therebeyond to reflect light up through the bottle.

3. Emulsifying apparatus comprising a casing which is closed at the top, bottom and ends but open at each side so that light may pass from one side to the other, a bottle holder surrounded by the casing, means for clamping a bottle against movement on the bottle holder, means for mounting the bottle holder in the casing to rotate about a horizontal axis so that the bottle is turned end over end when the bottle holder is rotated, means for rotating the bottle holder, a vertically-disposed light-diffusing plate mounted in the casing for cooperation with a bottle in the bottle holder, and light reflecting means provided on the bottle holder and disposed adjacent one end of the bottle and extending laterally therebeyond to reflect light up through the bottle.

4. Emulsifying apparatus comprising a rectangular casing which is closed at the top, bottom and ends but open at each side so that light may pass from one side to the other, a bottle holder surrounded by the casing, a pivoted lid mounted in the top of the casing and over the bottle holder, means for clamping a bottle against movement on the bottle holder, means for mounting the bottle holder in the casing to rotate about a horizontal axis so that the bottle is turned end over end when the bottle holder is rotated, means for rotating the bottle holder, a vertically-disposed light-diffusing plate mounted in the casing for cooperation with a bottle in the bottle holder, and light reflecting means provided on the bottle holder and disposed adjacent one end of the bottle and extending laterally therebeyond to reflect light up through the bottle.
